CONVERTIBLE BULKHEAD FOR
REFRIGERATOR CARS

Arthur F. O'Connor, Chicago, Ill., assignor to
Union Asbestos & Rubber Company, Chicago,
Ill., a corporation of Illinois

Application August 13, 1942, Serial No. 454,659

4 Claims. (Cl. 105—376)

The invention relates to convertible bulkheads for refrigerator and like cars. It is adapted for use in refrigerator cars having bulkheads which form one wall of an ice bunker in the end of the car, the bulkhead being movable to a stored position adjacent the end wall of the car. It is also adaptable for use in cars having bulkheads or load dividers movable longitudinally of the car and adapted to separate two or more types of lading.

More particularly, the invention relates to bulkheads which are suspended from rollers and tracks, of which there are numerous types in the prior art. The prior art shows bulkheads suspended from tracks and means for anchoring the bulkheads in different positions longitudinally of the car comprising latches, slide bolts and the like intermediate the bulkhead and the side walls of the car. The anchoring means on such structures are invariably separate members from the track on which the bulkhead moves.

The principal objects of this invention are to utilize the track (by the addition of small, inexpensive parts) as the anchoring means affixed to the car proper, and the elimination of anchoring means (brackets, sockets, hasps, etc.) on the side walls of the car. Any projection from or cavity in the side walls are highly objectionable as carton goods and other types of lading are damaged thereby when the lading shifts lengthwise of the car.

A further object is to provide an efficient means for automatically anchoring the upper portion of the bulkhead at the time the bulkhead is raised or lowered into its several operative positions, and to automatically free the upper portion of the bulkhead from its anchorage when it is raised or lowered. I show a lever means on the bulkhead for raising and lowering same but do not claim this lever means per se. I show the bulkhead in anchored position when it is lowered and I contemplate that the lower margin of the bulkhead will drop into a suitable slot or groove (not shown) at the time the upper margin drops into anchoring position, such means for anchoring the lower portion of the bulkhead being old in the art.

The above and other objects and advantages of the invention will be apparent from the following description of the embodiment shown in the accompanying drawings, in which—

Figure 1 is a schematic drawing showing the relation of the bulkhead to the car and the rel-

ative locations of the anchoring means on the bulkhead and car ceiling.

Fig. 2 is a fragmentary vertical sectional view taken along line 2—2 of Fig. 1, the extended bulkhead being shown in full lines and the stored bulkhead being indicated in dotted lines. The lever mechanism, for raising the bulkhead, is shown in this view also.

Fig. 3 is a fragmentary vertical sectional view taken along line 2—2 of Fig. 1, showing the bulkhead in raised position and the lever mechanism in locked position to hold the bulkhead in raised position.

Fig. 4 is a fragmentary perspective view of the bulkhead in anchored engagement with the track.

Fig. 5 is a fragmentary view taken along line 5—5 of Fig. 2, illustrating the lever mechanism for raising and lowering the bulkhead.

Fig. 6 is a fragmentary sectional view taken along line 6—6 of Fig. 3, showing the bulkhead in raised position and the anchoring means disengaged.

Fig. 7 is a fragmentary sectional view taken along line 7—7 of Fig. 5.

Fig. 8 is a fragmentary perspective view of the bulkhead, track and anchoring members, with the bulkhead in raised position and the anchoring means in inoperative position.

The car illustrated in the drawings may be a conventional refrigerator car having an end wall 10, top wall 12 and side walls 14, which may be of conventional insulated construction. The ceiling 16 of the car may extend in a single plane between opposed car end walls 10—10, but I prefer to provide an upwardly offset ceiling portion 18 adjacent each end wall, in order that the track means may be flush with or above the ceiling 16, eliminating projections downwardly therefrom which might interfere with lading extending to the ceiling 16. A hatch opening 20 may be provided in the top wall 12, at each corner thereof, for filling the ice bunkers with ice.

The bulkhead 22 may comprise a plurality of spaced apart vertical posts 24 secured at their upper ends by a horizontal capping strip 26 and at their lower ends by a similar strip (not shown). The posts 24 may comprise channel beams with side flanges carrying a wall portion 30 on the lading compartment side of the bulkhead. A foraminous wall portion 28 may be affixed to the posts 24 on the ice bunker side thereof.

The bulkhead may be suspended from a pair of

tracks 32 disposed longitudinally of the car and affixed to the ceiling 18 preferably equidistant from and on opposed sides of the longitudinal center of the car, by a pair of roller supported carriages 34 mounted upon the tracks 32, each carriage 34 having a strap 36 depending therefrom and extending downwardly through an aperture in the capping strip 26 and into the open channel of one of the posts 24. A bail-like lever 38 may be provided for raising and lowering the bulkhead and may comprise a pair of spaced apart levers located coincident with two of the posts 24 with their lower end portions extending into the channel portions of the posts and pivotally secured to the side walls thereof. The upper end portions of the spaced apart levers may be connected by a horizontal strap portion 40 whereby the spaced apart levers may be moved simultaneously by moving the strap portion 40. The lower end portion of each of the straps 36 may be pivotally secured to the lever 38 coincident therewith, the pivotal connection between the strap and lever being above the pivotal connection between the lever and the post. When the bulkhead is in lowered position the levers are in a substantially vertical position. When the strap portion 40 is moved or swung downwardly the pivot pin 42 acts as a fulcrum point for the levers and the bulkhead is lifted by the pivot pin 44. A suitable strut or detent 46 may be used to hold the levers in position to retain the bulkhead in raised position.

The track 32 may comprise an elongated inverted U-shape member having a horizontal top wall 48 abutting the ceiling 18, spaced apart depending vertical side walls 50 having inwardly turned marginal flanges 52 spaced from each other to form a slot extending longitudinally of the track on the under side thereof to permit the strap 36 to travel lengthwise thereof.

The description this far has been of refrigerator car construction which is not claimed herein as part of the present invention. The essential features of the invention are found in the improvements hereinafter described.

The track 32 may be provided with opposed longitudinal mounting flanges 54 welded to the track in coplanar alignment with the plane of the top wall 48 and provided with apertures to receive fastening bolts. Inasmuch as the tracks 32 of the invention will receive the thrusts received by the bulkhead, when the ice shifts against it from one side and the lading shifts against it from the opposite side, the purpose of the mounting flanges 54 is to permit the application of sufficient fastening bolts therethrough and into the ceiling structure to rigidly anchor the tracks against movement (loosening) longitudinally of the car. I contemplate also the use of cripples or bracing incorporated in the construction of the car top wall 12, intermediate the ceiling of the car and the roof of the car, to which the track fastening bolts may be secured. These cripples or bracing may comprise the conventional wooden beams or may comprise metal beams similar to carlines or purlines commonly used in car construction. The lower portion of each of the opposed side walls 50 of the track may be provided with a pair of longitudinally spaced detents 56, which I show as angles welded to the walls 50, but which may be made of various shapes without departing from the scope of the invention. The pair of detents 56 on one side wall 50 may be aligned, transversely of the track, with the pair of detents

on the opposed side wall, the space between the detents of each pair being centrally located with respect to the plane boundaries of the bulkhead in its extended, ice bunker forming position.

- 5 The opposed side walls 50, adjacent the end wall 10 of the car, may be provided with one detent 56 each, in transverse alignment on the track, as the stored bulkhead may contact a portion of the car end wall 10 to limit its movement in a 10 direction toward the end of the car. The upper margin of the bulkhead may be provided, coincident with each track 32, with a pair of up-standing walls 58 spaced from each other and disposed alongside the opposed walls 50 of the adjacent track. Each wall 58 may be provided at its upper portion with a laterally, inwardly projecting dentent 60 disposed in bulkhead anchoring position between the spaced apart detents 56 (when bulkhead is in lowered extended position). 15 20 When the bulkhead is raised, by the lever mechanism, the walls 58 and the detents 60 may be raised, with respect to the track 32 and the track detents 56, whereby the bulkhead detents 60 will be above the detents 56 and the bulkhead is 25 in position to be moved to the desired position longitudinally of the car. When the raised bulkhead is moved to the desired position it may be lowered by the lever mechanism, at which time the bulkhead detents 60 will be lowered 30 into holding engagement with the adjacent detents 56, thereby anchoring the bulkhead.

While I have shown the bulkhead in two anchored positions (fully extended and stored) I contemplate the use of additional detents 56 and 35 60 to permit the bulkhead to be anchored in a position intermediate the stored and fully extended positions, as, for instance, where a lesser amount of ice is required in the bunker or where a longer lading compartment is wanted between 40 the opposed bulkheads in bunker forming position.

While it is known to be possible to suspend the bulkhead from a single, centrally located track, I prefer to use a pair of tracks 32 intermediate the hatch openings 20, as this maintains the bulkhead with its upper and lower frame members parallel with the ceiling and floor of the car, respectively, and maintains the vertical sides of the bulkhead in parallel spaced 45 50 relationship with the car walls 14. In Fig. 1 of the drawings is shown a means for anchoring the upper side portions of the bulkhead, which comprises angles 62 secured to the ceiling, the vertical legs of which may be provided with detents 56. Angles 64 may be affixed to the upper frame of the bulkhead, the vertical legs of the angles being provided with laterally extending detents 60. This means for anchoring the upper side portions of the bulkhead requires less material than the intermediate anchoring means (the tracks 32) as the bulkhead is not suspended therefrom.

The accompanying drawings illustrate a preferred embodiment of the invention which is not limited to the exact details of construction shown and described, as it is obvious that various modifications thereof will occur to persons skilled in the art without departing from the scope of the claims.

70 I claim:

1. In a car having a transverse bulkhead movable longitudinally thereof, a track adjacent the top wall at a point removed from the side walls of the car, a roller riding on the track, lever means 75 on the bulkhead for raising and lowering the

bulkhead vertically, a member suspended from the roller connected to the lever means, a detent associated with the track intermediate its ends, a second detent on the bulkhead adapted to co-operate with said first named detent when the bulkhead is moved vertically in one direction and adapted to clear said first named detent when the bulkhead is moved vertically in the opposite direction, whereby to anchor the bulkhead and to permit movement thereof longitudinally of the car, respectively.

2. In a car having a transverse bulkhead movable longitudinally thereof, a track spaced from the side walls of and affixed to the car above the bulkhead, a roller supported by the track provided with a depending member, lever means on the bulkhead below the upper boundaries thereof adapted to raise and lower the bulkhead, said depending member being connected to said lever means, a detent associated with the track intermediate the ends thereof, a detent affixed to the bulkhead and disposed upwardly therefrom adapted to engage said first named detent when the bulkhead is moved vertically in one direction and adapted to clear said first named detent when the bulkhead is moved in the opposite direction whereby to limit the movement of the bulkhead in one direction longitudinally of the car and to permit movement of the bulkhead in said one direction, respectively.

3. In a car having a transverse bulkhead movable longitudinally thereof, a track adjacent the car ceiling in spaced relation with the car side walls, a roller supported by the track provided

with a depending member, lever means on the bulkhead operable to raise and lower the bulkhead, said depending member being connected at its lower portion to said lever means, a detent depending from the car ceiling in spaced relation with the car side walls, a detent extending upwardly from the bulkhead adapted to engage said first named detent when the bulkhead is moved vertically in one direction and adapted to clear said first named detent when the bulkhead is moved in the opposite direction whereby to limit the movement of the bulkhead and to permit the movement thereof in one direction longitudinally of the car, respectively.

4. In a car having a transverse bulkhead movable longitudinally thereof, a track adjacent the car ceiling, a roller supported on the track provided with a depending member, lever means on the bulkhead operable to raise and lower the bulkhead and having cooperative engagement with said member, a laterally extending detent on each opposed side of the track intermediate its ends, spaced apart members projecting upwardly from the bulkhead coincident with the track, each of said spaced apart members being provided with a laterally extending detent adapted to co-operate with one of the detents on the track when the bulkhead is moved vertically in one direction and adapted to clear said last named detents when the bulkhead is moved vertically in the opposite direction whereby to limit the movement of and permit the movement of said bulkhead longitudinally of the car, respectively.

ARTHUR F. O'CONNOR.
